(57) **CLAIM**

I claim the ornamental design for a portable stool, as shown
and described.

DESCRIPTION

FIG. 1 is a perspective view of a portable stool.

FIG. 2 is a front elevation view of the portable stool.

FIG. 3 is a first side elevation view of the portable stool.

FIG. 4 is a rear elevation view of the portable stool.

FIG. 5 is a second elevation view of the portable stool oppo-
site the first side elevation view; and,

FIG. 6 is a top plan view of the portable stool.

The broken lines shown in the drawings depict environmental
features that form no part of the claimed design.
